UNITED STATES PATENT OFFICE

2,461,977

DETACHABLE SHOE HEEL ORNAMENT

Thomas Gilmour, Brooklyn, N. Y.

Application July 13, 1946, Serial No. 683,391

5 Claims. (Cl. 41—10)

1

The present invention concerns ornaments for the heels of ladies' shoes and refers more particularly to the type comprising a body adapted to overlay a portion of the heel's peripheral surface and comprising portions substantially embracing said periphery, together with fastening means adapted to engage the front face of the heel.

An object of the present invention is to provide an ornament of the type described which shall be quickly applicable and removable from the heel so as to constitute a separate item of apparel which may be worn or not as dictated by the nature of the other items of the costume.

A further object is to provide a heel ornament of cheap construction so that a variety of such ornaments in different designs may be owned at a small expenditure of money.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of a heel with the preferred form of the invention applied thereto.

Fig. 2 is a perspective view of the preferred form of the invention.

Fig. 3 is a fragmentary bottom elevation thereof.

Fig. 4 is an enlarged front elevation partly in section, of a fragment of the preferred form of the invention.

Fig. 5 is a perspective view of a modified form of the invention.

Fig. 6 is a perspective view of the latter applied to a heel.

Fig. 7 is a section on the line 7—7 of Fig. 6.

Fig. 8 is a perspective view of a further modification of the invention.

Referring now in detail to the drawings, the preferred embodiment of my invention is the ornament 10, comprising a body portion 11 which is shown as a band of light sheet metal carrying exteriorly a design 12 which may be applied thereto in any convenient and well known manner. The body 11 should be at least moderately flexible in order to snugly fit various heels to which it may be applied.

Ornament 10 is shown applied to a heel 13, and for the purpose of this description the front (the slightly concave surface 14 of the heel will be called the font) and the downwardly and in-

2

wardly tapering, generally parti-cylindrical surface 15 extending on the sides and back of the heel and bounded by the corners 16, will be called the outside surface of the heel.

5 Pivots connected to each end of body 11 as by the hinges 17 are the clips 18, shown as substantially rectangular flat rigid bodies comprising the sharpened prongs 19 extending substantially perpendicularly from their outer border portions.

10 Each hinge 17 comprises the central pin 20 and wound about pin 20 within hinge 17 is the torsion coil spring 21, the ends 22 and 23 of which are soldered, as at 24, to clip 18 and body 11 respectively. A finger catch 25 extends from each clip 18.

15 In operation and use, the ornament 10 is applied to heel 13 so that a body 11 encompasses the outside surface 15 thereof, the hinges 17 being even with corners 16 and clips 18 extending inwardly of face 14 and towards each other. Prongs 19 are urged against face 14 by springs 21, the direction of action of which is indicated by the arrows in Figs. 2 and 3.

20 25 Prongs 19 should be pushed into face 14 manually, and are thus effective to prevent motion of any kind in any part of ornament 10, while springs 21 prevent the prongs coming out. Springs 21 further exert a circumferential tension on body 11 as the reaction to the torsional compression exerted on clips 18.

30 35 Ornament 10 may be easily removed whenever desired by engaging the finger catch 25 with the fingernail and loosening prongs 19.

40 A modification of the invention is shown in Figs. 5, 6 and 7, wherein a band shaped body 30 comprises elastic end portions 31 furnished with the male components 32 of snap fasteners. Heel 33 is furnished with the female components 34 of the snap fasteners. Utmost freedom of choice of material for body 30 is enjoyed in this form of the invention, since body 30 may be semi-rigid as body 11, or may be of textile material, either elastic or non-elastic.

45 50 Raised ornamentation such as artificial jewels 35 may be applied in any well known manner to body 30.

It is of course understood that the bodies 11 and 30 may be of irregular outline, and that one or more of them may be used on the heel at the same time if so desired.

Fig. 8 shows a body portion 40 which covers entirely the surface of the heel which it fits. The ornamentation 41 is applied over the entire 55 area of the body portion as shown. Snap fas-

tening elements 42 are used, but if preferred sharpened prongs similar to those in the previous form may be substituted. The body portion 48 is hinged as at 43.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A heel ornament comprising, in combination, a body portion adapted to encompass the outside surface of a heel, a clip portion pivotally connected thereto, and a spring actuating said clip portion against said heel.

2. A heel ornament comprising, in combination, a body portion adapted to encompass the outside surface of a heel, a clip portion pivotally connected thereto, prongs extending substantially perpendicularly from said clip portion, and a spring actuating said clip portion against said heel.

3. In a heel ornament for a heel comprising a front surface and an outside surface, an ornament body adapted to encompass said outside surface, a clip pivotally connected to each end of said body, and spring means engaging said body and said clip to urge the latter against said front surface.

4. In a heel ornament for a heel comprising a

front surface and an outside surface, an ornament body adapted to encompass said outside surface, a clip pivotally connected to each end of said body, and spring means engaging said body and said clip to urge the latter against said front surface, said clip further comprising finger catch means.

5. In a heel ornament for a heel comprising a front surface and an outside surface, an ornament body adapted to encompass said outside surface, a clip pivotally connected to each end of said body, and spring means engaging said body and said clip to urge the latter against said front surface, said spring means comprising a torsion coil spring located within the pivotal connection between said body and said clip.

THOMAS GILMOUR.
